UNITED STATES PATENT OFFICE

ADOLPH G. LOTTER, OF MILWAUKEE, WISCONSIN, ASSIGNOR TO STATIONERS LOOSE LEAF COMPANY, OF MILWAUKEE, WISCONSIN, A CORPORATION OF WISCONSIN

LOOSE LEAF BINDER

Application filed September 2, 1931. Serial No. 560,752.

This invention relates to improvements in loose leaf binders and refers more particularly to binders of that type having rigid posts with which one head member is detachably and adjustably connected.

It is an object of this invention to provide a locking structure entirely contained within the binder head and which affords simple and effective means of securing between the head and the post and is so constructed that any tendency to spread the heads merely increases the grip between the locking means and the post.

Another object of this invention is to provide a locking device of the character described which is so constructed as to permit the upper binder head to be moved toward the body of leaves without requiring the actuation of unlocking mechanism.

In loose leaf binders of the character heretofore in use, the means for releasing the locking device has been such that the normal handling of the binder caused it to shift and release the locking device. This accidental unlocking of the binder permitted leaves to drop out and very often resulted in serious confusion of records. It is therefore a further object of this invention to provide locking means for securing a binder head to a post which may be released merely upon the shifting of a button or other suitable actuating member, but which embodies means for preventing accidental shifting of the button even during rough handling.

With the above and other objects in view which will appear as the description proceeds, this invention resides in the novel construction, combination and arrangement of parts substantially as hereinafter described and more particularly defined by the appended claims, it being understood that such changes in the precise embodiment of the herein-described invention may be made as come within the scope of the claims.

In the accompanying drawing one complete example of the physical embodiment of this invention is illustrated constructed according to the best mode so far devised for the practical application of the principles thereof, and in which:

Figure 1 is a view illustrating the back of a loose leaf binder constructed in accordance with this invention, portions thereof being broken away and shown in section to illustrate structural details;

Figure 2 is a longitudinal section view taken through Figure 1 on the plane of the line 2—2;

Figure 3 is a detail section view illustrating the manner of releasing the locking means;

Figure 4 is a perspective view of one of the locking elements; and

Figure 5 is a fragmentary detail view illustrating the manner of mounting the locking elements.

Referring now more particularly to the accompanying drawing, the numerals 5 and 8 represent the lower and upper binder heads, respectively, of a conventional loose leaf binder and between which a body of leaves 7 is clamped, the leaves being impaled upon two rigid binder posts 6 extended upwardly from the lower binder head 5.

The upper binder head 8 is removable and is preferably of tubular construction having top and bottom walls 9 and 10 respectively connected by side walls 11. In the present instance it is composed of two channel sections secured together with the edges of their flanges abutting to form the sides 11, by rivets 12. The rivets 12 also pass through end members 13 which provide means for attaching a cover 14 to the binder head as is customary. The top and bottom walls 9 and 10 have aligned openings 15 and 16, respectively, to receive the posts; and within the tubular head and adjacent each post is a locking element indicated generally by the numeral 17, for releasably locking the upper binder head 8 to the posts.

Inasmuch as both locking elements 17 are identical in construction a specific description of one will suffice for both.

The locking element consists of a stiff flat plate member 18 apertured as at 19 to receive the post. The aperture 19 is slightly greater than the diameter of the post. At one end the plate member 18 has oppositely extending lugs 20 which are received in openings 21 formed in the side walls 11 so that the plate

member 18 is pivotally mounted for movement about an axis spaced from and at right angles to the axis of the post and elevated from the bottom wall 10 of the binder head.

5 The opening 21 is preferably formed by notching the side flanges of the channel forming the upper portion of the binder head and the location of the pivotal mounting is such that the flat plate member normally assumes 10 an inclined position causing the upper edge 22 and the lower edge 23 of its aperture 19 to engage the opposite surfaces of the post.

In this inclined position with its diagonally 15 opposite edges 22 and 23 of its aperture engaging the post, it is observed that the extreme lower end of the plate member, which is rounded as at 24 for a purpose to be later described, is above the adjacent bottom wall 10 of the binder head, so that upon any 20 tendency toward removal of the binder head 8 from the post, the plate member is free to move toward a greater inclination causing the edges 22 and 23 of its aperture 19 to bite into the post and thus prevent such movement of the binder head with respect to the post. Engagement of the binder head onto the post, however, is permitted for the reason that during such movement of the binder head, the engagement of the edges 22 and 23 25 with the post tends to elevate the plate member.

As will be readily apparent, the plate member assumes an inclined position by gravity when the binder head 8 is in its normal position, but to positively insure the maintenance 30 of the desired inclination on the part of the plate member, a light spring 25 is provided.

This spring, as best illustrated in Figure 4, 35 is formed of a single piece of spring wire bent 40 to substantially U shape with its closed end 26 engaging the upper face of the lower end of the plate member and with its legs 27 bent as at 28 to pass through notches 29 in the 45 opposite sides of the plate member and continue along the bottom face of the plate member, towards the upper edge 30 of the plate member. The legs 27 of the spring project 50 beyond this edge and are curled as at 31 and then extend back toward the closed end 26 of the spring. When in position these free ends 55 of the spring 25 engage the undersurface of the top wall 9 of the binder head as clearly shown in Figure 1 so that the action of the spring forces the free lower end of the plate member downwardly.

With the binder head 8 in position on the posts, removal is impossible unless the plate members of the locking elements are moved out of their normal inclined position to dis- 60 engage their biting edges 22 and 23 from the post members, and to effect such lifting of the plate members, a releasing member indicated generally by the numeral 32, is provided. This releasing member is preferably stamped 65 from a single strip of sheet metal and is bi-

furcated at both ends as at 33 to provide spaced legs 34 which straddle the posts.

The spaced legs 34 are inclined upwardly in the same direction from the plane of the major portion of the member 32 as at 35 and 70 36, and upon longitudinal shifting of the member 32, engage the lower rounded edges 24 of the plate members to lift the same out of their normal inclined position, as illustrated in Figure 3, and release the posts from 75 the biting edges 22 and 23.

The major portion of the releasing member 32 slidably rests on the bottom 10 of the binder head and adjacent the center of the binder head, the member 32 is bent up at 80 spaced points as at 37 to position the portion 38 therebetween, directly beneath the top wall 9. A longitudinal slot 39 is cut into the portion 38 to receive the free end of a flat spring member 40, the opposite end of which 85 is riveted or otherwise secured as at 41 to the releasing member.

The free end of the flat spring member carries an actuator 42 which projects through an opening 43 in the top wall of the binder head. The actuator 42 has an enlarged finger 90 engaging button 44 and a stem 45 provided with a lower section 46 of large diameter and an upper section 47 of smaller diameter.

The opening 43 is of double key-hole shape with large end portions 48 connected by a narrow intermediate portion 49 of less width than the diameter of the lower section 46, and the normal position of the button under the action of its flat spring 40, which is comparatively stiff, is such that the lower section 46 of larger diameter is in the plane of the top wall 9. Hence when the stem is at either end of the opening 43, its portion 46 of larger diameter is in either one of the opening end portions 48 preventing longitudinal shifting of the releasing member 32 in either direction until the actuating button is depressed to align the upper section 47 of small diameter with the top wall 9.

From the foregoing description taken in connection with the accompanying drawing, it will be readily apparent to those skilled in the art to which an invention of the character described appertains, that the locking means of this invention is particularly well adapted for use with loose leaf binders of the character described and that it provides automatically operable means for locking the binder head onto the posts to permit ready engagement of the binder head with the posts but to positively preclude any movement whatsoever of the binder head from the posts, except when the locking means is released.

It is also apparent that the releasing member cannot shift accidentally to release the locking means, nor will the locking means jar loose during even comparatively rough handling of the binder.

What I claim as my invention is:

1. In a loose leaf binder including spaced posts, a hollow binder head apertured to receive the posts, means for locking the binder head against removal from the posts comprising, normally inclined plate members having portions cut away to define biting edges between which the posts are received, the inclination of the plate members causing the biting edges to engage the posts with great force upon any tendency toward removal of the binder head from the posts, a longitudinally shiftable releasing member within the binder head simultaneously engageable with the plate members to move the same out of their normal inclined positions to enable removal of the binder head from the posts upon movement in one direction, an actuating member for moving said releasing member, and cooperating means carried by the actuating member and the binder head for positively holding the releasing member in either of its extremities of movement.
2. In a loose leaf binder including a post and a hollow binder head apertured to receive the post, means for locking the binder head against removal from the post including an inclined plate member having an aperture to receive the post, the inclination of the plate member causing opposite edges of the aperture to bite into the post, a releasing member for moving the plate member out of its inclined position, said releasing member being movable within the binder head, an actuating member having a portion without the binder head for moving the releasing member, cooperating means carried by the actuating member and the binder head for holding the releasing member at either of its limits of movement, and spring means mounting the actuating member on the releasing member and maintaining the actuating member in a position with the said cooperating means in operative relation.
3. In a loose leaf binder including a post and a hollow binder head engageable with the post, locking means carried by the binder head for securing the same on the post, a longitudinally shiftable releasing member for releasing the locking means and mounted within the binder head, an actuating member for shifting the releasing member and having a part projecting through an opening in one wall of the binder head to position a portion thereof outside the binder head, said actuating member part extending through the opening in the binder head wall having portions of different diameters and the opening being substantially of double key hole shape whereby the engagement of the actuating member part of larger diameter with either end of the opening precludes shifting of the releasing member, and spring means mounting the actuating member on the releasing member and urging the same to a position with its part of larger diameter in the plane of the binder head wall.
4. In a loose leaf binder including a post and a hollow binder head engageable with the post, locking means for securing the binder on the post, releasing means shiftable within the binder head for releasing the locking means, an actuating member for the releasing means, a flat spring member fixed to the releasing means and mounting the actuating member with a portion thereof projecting through an opening in one wall of the binder head, said opening being of substantially double key hole shape with enlarged ends connected by a narrow intermediate slot, and the actuating member part projecting through the opening having portions of large and small diameters, shifting of the releasing member being prevented by the engagement of the actuating member part of large diameter with either end portion of the opening and the spring yieldably urging the actuating member to a position with its part of large diameter in the plane of said binder head wall.
5. In a loose leaf binder including a post and a hollow binder head engageable therewith, a flat element apertured to receive the post, means hingedly mounting said flat element on the binder head in such a manner that the flat element, when the binder head is in its normal position, assumes an inclined position causing the walls of said aperture to bite into opposite sides of the post, releasing means for moving said flat element out of its inclined position to release the locking engagement between the walls of said aperture and the post, an actuator carried by the releasing means and extending through an opening in one wall of the binder head, and means on the actuator selectively engageable behind abutments formed by enlargements at opposite ends of the opening in the binder head wall to hold the actuator and the releasing means against accidental actuation from either of their positions of adjustment.
6. In a loose leaf binder including a post and a hollow binder head engageable therewith, a locking element within the binder head and engageable with the post for securing the binder head and post against relative movement in one direction, means mounting said locking element for movement to and from operative position, a releasing member within the binder head and shiftable to move the locking element out of one position and towards the other, an actuator carried by the releasing member and extending externally of the binder head, and a connection between the actuator and the binder head for securing the releasing member against accidental actuation from either of its limits of movement, said connection requiring depression of part of said actuator into the binder head to effect its release.

7. In a loose leaf binder including a post and a hollow binder head engageable therewith, locking means within the binder head adapted to secure the binder head against movement in one direction with respect to the post, a releasing member longitudinally shiftable within the binder head to actuate the locking means, an actuator carried by the releasing means and having a part yieldably projected through an elongated opening in one wall of the binder head, said actuator part and the elongated opening, being of such relative configuration and size as to effect an interlocking connection when the actuator is at either end portion of the slot to secure the actuator and consequently the releasing member against accidental actuation from either position of adjustment, and said interlocking connection requiring depression of the actuator to release the same.

In testimony whereof I have hereunto affixed my signature.

ADOLPH G. LOTTER.
